UNITED STATES PATENT OFFICE

131,872

DESIGN FOR A MEDAL OR SIMILAR ARTICLE

Linus F. Heberger, Rochester, N. Y., assignor to
The Metal Arts Company, Inc., Rochester, N. Y.

Application January 22, 1942, Serial No. 105,373

Term of patent 3½ years

To all whom it may concern:

Be it known that I, Linus F. Heberger, a citizen of the United States, residing at Rochester, in the county of Monroe and State of New York, have invented a new, original, and ornamental Design for a Medal or Similar Article, of which the following is a specification, reference being had to the accompanying drawing, forming a part thereof.

I claim:

The ornamental design for a medal or similar article, as shown.

LINUS F. HEBERGER.
